KNITTED FABRIC

Harry Fleisher, Watertown, Conn., assignor to
 Princeton Inc., Watertown, Conn., a corpora-
 tion of Connecticut

Application February 19, 1936, Serial No. 64,667

1 Claim. (Cl. 66—169)

This invention relates to knitted fabrics, such as are made upon a circular knitting machine employing a series of independent spring beard needles.

5 One object of this invention is to provide a run-resisting fabric including plain stitches and tucks having a ribbed surface on one side forming an improved and highly attractive appearance.

10 A further object is to provide a fabric of the above nature made with a machine in which the closing of the needle beards is controlled by a series of pressers and presser cams of special shape, and so arranged as to omit the pressing of 15 the beards of certain needles so as to cause said needles to form tucks instead of casting off the old loops.

A further object is to provide an improved 20 knitted fabric of the above nature having a linen-like appearance, which will be simple and easy to manufacture, flexible, having good elasticity in the width, which will not sag in the length, which will be non-crushable, and very efficient and durable in use.

25 With these and other objects in view, there has been illustrated on the accompanying drawings one form in which the invention may be conveniently embodied in practice.

In the drawings:

30 Fig. 1 represents a diagrammatic plan view of a circular knitting machine upon which the improved fabric may be constructed.

Fig. 2 is a table showing the relative arrangement of the pressers and presser cams, and giving the sequence in which the stitches and tucks 35 will take place in the respective wales and courses.

Figure 3a is a perspective view of a "plain" 40 presser cam.

Figure 3b is a perspective view of a "high cut" 45 presser cam.

Figure 3c is a perspective view of a "low cut" 50 presser cam.

Fig. 4 is a fragmentary perspective view of the 55 twelve beard pressers arranged in sequence.

Fig. 5 is a side fragmentary view showing the engagement of a low cut presser cam with a low cut 60 presser, the needle beard being closed and casting off the stitch.

Fig. 6 is a similar view showing the engagement of a low cut presser cam with a high cut 65 presser, the needle beard remaining open for making a tuck.

Fig. 7 is a similar view showing the engagement of a high cut presser cam with a low cut 70

presser, also allowing the needle beard to remain open for producing a tuck.

Fig. 8 is a similar view showing the engagement of a high cut presser cam with a high cut presser, resulting in the closing of the needle beard and casting off the stitch.

Figs. 9 and 10 indicate the appearance of the front and rear sides of the improved fabric, respectively.

Fig. 11 is a view on an enlarged scale showing 10 the stitch structure of the knitted fabric.

Referring now to the drawings in which like reference numerals denote corresponding parts throughout the several views, the numeral 10 indicates a series of identical needles which are 15 carried on a rotating cylinder, not shown, said needles being independently raised and lowered at each knitting point by suitable cams, not shown, as in ordinary practice.

Each of the needles 10 is provided at its upper 20 end with the usual spring beard 11 which is adapted to hook over the yarn or thread to form loops in the knitting operation. Located between the successive needles 10 are the usual cam-operated sinkers, not shown. Provision is also 25 made of a plurality of beard closers or pressers—one for each needle 10—, which are adapted to close the needle beards 11 when moved by the presser cams to be hereinafter described.

The beard closers or pressers are made in two 30 forms; i. e., "low cut", as indicated by 12, and "high cut", as indicated by 13. The low cut pressers 12 have slots 14 cut in their edges a short distance from the upper ends thereof, while the high cut pressers have their upper 35 corners removed, forming angular slots 15, the slots 14 and 15 being located at different heights and out of alignment with each other.

The presser cams are made in three different forms; i. e. "plain", "low cut", and "high cut", as 40 indicated in Fig. 3 by the numerals 16, 17 and 18, respectively. In the low cut presser cam 17 the lower front corner is removed to provide an angular recess 19 while in the high cut pressure cam 18, the upper front corner is removed to 45 provide an angular recess 20.

The low and high cut pressers 12 and 13 are arranged in succession around the knitting machine in the sequence indicated in the top horizontal row of the table of Fig. 2; to wit: L—L— 50 H—L—H—L—H—L—H—L—H, this sequence being repeated over and over again. This arrangement is also shown in Fig. 4.

The plain presser cams 16, the low cut presser 55 cams 17, and the high cut presser cams 18 are

- located at the knitting points, and as shown in Fig. 1, are arranged in the sequence given in the right-hand vertical column on the table of Fig. 2; to wit: P—H—L—L—L—P—H—L—L—L—L—L.
- 5 The locations of the twelve presser cams employed are clearly shown in Fig. 1. The pressers and presser cams are so arranged that whenever a plain presser cam 16 engages either a low cut presser 12 or a high cut presser 13, a stitch will occur; whenever a high cut presser cam 18 engages a low cut presser 12, a tuck will occur; and the same result will also take place when a low cut presser cam 17 engages a high cut presser 13. In all other cases, the yarn will be cast off.
- 10 The arrangement of the stitches and tucks thus produced in the knitted fabric is clearly indicated by the tabulation in the body of the table of Fig. 2, and the actual appearance of the fabric is shown in Figs. 9 and 10. Figs. 5 and 8 represent two of the conditions when stitches will be produced, while Figs. 6 and 7 indicate when tucks will occur.
- 15 In Fig. 5 the engagement of a low cut presser cam with a low cut presser causes the needle beard to be closed, and the same result takes place in Fig. 8 where a high cut presser cam engages a high cut presser. In Figs. 6 and 7, however, the needle beards will remain open due to the fact that a low cut presser cam engages a high cut presser in Fig. 6, and a high cut presser cam engages a low cut presser in Fig. 7, respectively.
- 20 The yarn is fed into the machine in twelve different strands indicated by the numerals 21,

22, 23, 24, 25, 26, 27, 28, 29, 30, 31 and 32, respectively in Fig. 1. The strands are delivered to the needles 10 through the usual guides 33 and 34.

It will be noted by referring to Fig. 9 that than an attractive ribbed "ratine" or "boucle" appearance is produced on the front of the fabric, and it will be understood that this construction contributes to run-resisting properties thereof.

While there has been disclosed in this specification one form in which invention may be embodied, it is to be understood that this form is shown for the purpose of illustration only, and that the invention is not to be limited to the specific disclosure but may be modified and embodied in various other forms without departing 15 from its spirit. In short, the invention includes all the modifications and embodiments coming within the scope of the following claim.

Having thus fully described the invention, what is claimed as new, and for which it is desired 20 to secure Letters Patent is:

A run resisting knitted fabric repeating every six courses and every twelve wales, which comprises a yarn knitted in each of said wales in the first course, a yarn tucked in two wales, knitted, 25 tucked, knitted, tucked, knitted in two wales, tucked, knitted, tucked and knitted in that order, in the said twelve wales of the second course, and four yarns, one in each of the third, fourth, fifth and sixth courses, knitted in two wales, tucked, 30 knitted, tucked, knitted, tucked in two wales, knitted, tucked, knitted and tucked, in that order, in the said twelve wales of said four yarns.

HARRY FLEISHER.
